UNITED STATES PATENT OFFICE.

CATHERINE O'HARA, OF NEW YORK, N. Y., ASSIGNOR TO THE BUTTERICK PUBLISHING COMPANY, (LIMITED,) OF SAME PLACE.

DESIGN FOR A LADY'S POLONAISE.

SPECIFICATION forming part of Design No. 15,590, dated December 2, 1884.

Application filed September 12, 1884. Term of patent 3½ years.

To all whom it may concern:

Be it known that I, CATHERINE O'HARA, of the city, county, and State of New York, have invented and produced a new and original Design for a Pattern of a Lady's Polonaise, (numbered 9,406;) and I do hereby declare that the engraved prints accompanying this specification convey to any one accustomed to using paper patterns a clear understanding of how 5 to a garment made up by the pattern will appear.

The design shows closely-fitted single-breasted-polonaise fronts, each exhibiting a straight edge and flaring in a point below the closing, 15 rounding upward toward its back edge, and displaying draping plaits in its back edge, a

deep polonaise-back that exhibits a high draping upon the outside at the lower end of the center body-seam, displays deep loopings, alike at both sides, high up in the front edges, 20 and under-loopings at the center, and falls in deep straight plaits below the drapings, coat-sleeves, and a standing collar.

What I claim as my invention, and desire to secure by Letters Patent, is—

The design for a lady's polonaise, as shown in the engraved prints accompanying this specification.

CATHERINE O'HARA.
